United States Patent Office

Des. 182,539
Patented Apr. 15, 1958

182,539

MAN'S HOSE OR A SIMILAR ARTICLE

George T. Sor Relle, Chicago, Ill.

Application November 13, 1956, Serial No. 43,735

Term of patent 3½ years

(Cl. D47—7.2)

Fig.1

Fig.3

Figure 1 is a perspective view of a man's hose, or a similar article, showing my new design;

I claim:

The ornamental design for a man's hose or a similar article, substantially as shown and described.
